UNITED STATES PATENT OFFICE

2,004,270

STROBOSCOPIC APPARATUS AND METHOD

Peter Davey, Mount Vernon, N. Y., assignor to
 Vibroscope, Inc., New York, N. Y., a corpora-
 tion of New York

Original application January 26, 1926, Serial No.
 83,984. Divided and this application July 29,
 1931, Serial No. 553,775

19 Claims. (Cl. 176—124)

My invention relates to the stroboscopic examination of moving bodies. Its primary object is to provide apparatus, and also a method of operation, whereby flash-illuminating stroboscopes can be made to produce sharp and well defined images throughout a wide range of flash-frequencies, and especially throughout a wide speed range, such as substantially throughout the whole range of machine speeds likely to be encountered in practice, say from 100 R. P. M. to 10,000 R. P. M. or more. This application is a division from my co-pending application Serial No. 83,984, filed January 26, 1926.

The accompanying drawing illustrates a preferred form of my invention. Figure 1 is a diagrammatic illustration of an entire stroboscope embodying the present invention. Figure 2 is a perspective of the interrupter unit thereof. Figure 3 is a longitudinal section of the interrupter unit. Figure 4 is a section of the same on line IV—IV of Fig. 3; the line III—III indicates the section of Fig. 3. Figure 5 is a section on the line V—V of Fig. 3. Figure 6 is a conventional representation of discharges of an oscillating circuit, and Figure 7 is a diagrammatic illustration of another form of the present invention.

The stroboscope in connection with which the present invention is here illustrated comprises three separate units (Fig. 1), the illuminator A, the transformer or inductor unit B which provides the electric currents which light the illuminator, and the interrupter unit C which controls the time of lighting the illuminator. These three are united by flexible leads long enough to permit the separate units to be disposed in convenient locations, that is to say, the unit B set down in operation in any convenient place, the interrupter C applied to a suitable driving shaft even though somewhat remote from the unit B, and the illuminator approached close to the part to be examined independent of the location of B and C.

The illuminator A is an apparatus of the kind which is quickly lighted on the passage of an electric current and quickly darkened when the current ceases, such as a neon tube, in which discharges take place between two electrodes in neon gas at sub-atmospheric pressure. I herein use the term "flash illuminator" as a generic term to include the various forms which apparatus suitable for use at A may assume. I customarily mount this apparatus on a handle or holder with a suitable light reflector A₁ at one side of it so that the light can be conveniently

approached to and directed on the particular moving part to be studied.

The transformer or induction coil which raises the voltage of the electric currents for the illuminator A is preferably contained in a case or box B as diagrammatically outlined in Fig. 1. The secondary winding or circuit of the transformer is connected to the terminals of the neon tube A as illustrated, i. e. by means of the rather long flexible leads A₂. The primary or inducing winding is connected to a source of energy such as the battery 20, and in series therewith to the contacts 16 and 18 of the interrupter unit C. The transformér, it will be understood, transforms energy received from the source 20 into an electric current of suitable voltage to light the illuminator whenever interrupter contacts 16 and 18 are actuated. In the present instance the core of the transformer is of iron, open magnetic circuit, and the primary circuit is of the closed circuit type, energy being stored in the core of the transformer in the form of magnetism created by the current in the primary circuit when the contacts 16 and 18 are closed, and being released to the secondary circuit and illuminator when the contacts separate. In order to adapt the instrument to various shaft speeds, I have provided the primary winding of the transfer with taps as hereinafter explained and the multi-pole switch B₁ serving these taps is usually attached to the wall of the box so as to be accessible from the outside as indicated in Fig. 1. Ordinarily I use a battery 20 to supply the electric current to energize the transformer and this may be included in the transformer case, but usually I place it outside and connect it to the circuits through binding posts located in the wall of the transformer box B as also diagrammatically indicated in Figure 1.

The interrupter unit C (outlined in Fig. 1 and shown in detail in Figs. 2 to 5) contains the contacts 16 and 18 in the circuit of the primary winding of the transformer, and the interrupter shaft 6 which opens and closes them. The unit also embodies the adjustment features which permit the body under examination to be viewed in any position throughout its cycle, and mechanism whereby the number of flashes per rotation of the shaft 6 can be varied at will. The head 1 of this unit has a central projecting cylindrical boss 2 on which a rotatable sleeve 3 is mounted; a cover 4 extending from the periphery of the head 1 houses the various other mechanism, and a screw or screws 5 fastens the cover to the head. The shaft 6 projects from

the enclosure of this cover through the boss 2 and a ball bearing 7 mounts the shaft in the sleeve 3. This bearing not only acts as a radial bearing, but also holds the shaft against end-
wise movement with respect to the sleeve. The collar 8 on the shaft conceals the bearing and
protects it from dirt. The shaft 6 also has a
radial bearing, rather long or extended, in the
boss 2; this tends to reduce vibration, and with-
in this long bearing a circumferential groove
10 is provided for lubrication purposes. On the
outer end of the shaft 6 is a centering point 11
to be pressed against the end of a shaft (say of
the machine under examination) which is ro-
tating at such a speed as to produce the proper
number of interruptions of the primary circuit
as will be understood. The frictional engage-
ment of a centering point 11 with the driving
shaft is quite sufficient to drive the interrupter,
and because of its simplicity and convenience
this is a very desirable arrangement for driving
stroboscopes, or at least for driving portable
stroboscopes. The shaft 6 actuates the contacts
16 and 18 by a cam 12 on its opposite end, which
is arranged to strike a lever 15 carrying the
contact 16 and which is so biased by the spring
17 as to hold the contact 16 in engagement
with the stationary adjustable contact 18, except
when lifted by the cam. Usually I place a block
21 on the lever to receive the blows of the cam
or cams. The lever 15 and contact 18 are con-
veniently mounted on a plate 14 attached to
the head 1 as shown, and as before indicated,
rather long flexible conductors 34, entering the
box B through the insulator 36^b (Fig. 1), con-
nect the contacts 16 and 18 to the primary wind-
ing of the transformer B and the source of en-
ergy 20 in series as shown in Fig. 1. The con-
denser to reduce the arcing or sparks at the
contacts 16 and 18, appears at 19, and is con-
nected in shunt to the contacts 16 and 18. I
have found that it is important in flash-illumi-
nating stroboscopes that this condenser be
placed as close to the interrupter contacts as
possible, and I therefore mount it in or as a part
of the interrupter unit. It may be fixed to the
plate 14 as shown in Fig. 3. The cam 12 lifts
the contact 16 off the contact 18 once in each
rotation of the shaft 6 as will be apparent.
Other cams may be put on the shaft 6 to cause
the contacts 16 and 18 to open more than once,
at will, in each rotation of the shaft. Another
such cam is shown at 13, and this cam is shown
as displaced angularly 180° from the cam 12
and also displaced from the cam 12 longitudi-
nally of the shaft so that by adjustment either
the cam 12 alone or both cams 12 and 13 may
be made to strike the lever 15. Cam 13 there-
fore, by proper adjustment, in cooperation with
cam 12 provides for interrupting the primary
circuit twice in each shaft rotation and at op-
posite points in the cycle. To bring different
cams into operative relation to a lever such as
15, I have found it important that the lever be
mounted immovable axially and the cams be ar-
ranged for axial adjustment, rather than that
the lever be mounted for axial adjustment on its
fulcrum pin and the cams fixed axially as has
been proposed heretofore. My construction pro-
duces a simpler motion of the lever and more
reliable operation. I have therefore mounted
the lever 15 in fixed axial position on the plate
14 and arranged the shaft 6 to slide, carrying
its cams 12 and 13 with it. To slide the shaft
75 to the left or right, the sleeve 3 is slid on the
boss 2, and a ball or balls 22 pressed by springs
23 in the boss coat with two grooves 25 on the
inner periphery of the sleeve to define the two
positions of the shaft and frictionally hold the
sleeve and shaft in each of these positions until
manually moved at the will of the operator.
When the shaft 6 is in its right hand position
as shown in Fig. 3, only the cam 12 strikes the
lever 15 as before described. When the shaft
is moved to the left however (with respect to
Fig. 3) the cam 13 is also brought into position
to strike the block 21, and the latter being wide
enough to be struck by the cam 12 when the
shaft is to the left as well as when it is to the
right, the lever 15 is then actuated twice in each
rotation of the shaft and the engagement of 16
with 18 is broken twice, bringing about two light
flashes in the illuminator for each shaft rota-
tion in the place of one when the shaft is in its
right hand position.
A second function of the balls 22 is to impose
sufficient frictional resistance between sleeve 3
and the boss 2 to prevent the head 1 turning
with the shaft. A pin 29, the inner end of which
is flattened underneath the lever 15, can be
turned at will by the nubbed head 30 and when
turned temporarily retains the contact 16 out
of engagement with the contact 18; a sight plate
31, fixed to turn with the pin 29 is exposed
through a port 32 and conveniently marked, as
with "Off" and "On", to indicate whether the
contact 16 is held off the contact 18 or whether
the instrument is in condition for operation.
The same plate 31 may cooperate with pins
33 to restrict the turning movement of the pin
29 to the desired limits, while notches in the
cover cooperating with a ball pressed by a spring
35 on the plate 31 (see Fig. 3) holds the pin
frictionally in its two extreme positions.
In operation, the coil case and battery (if
any) are set down in any location convenient
to the machine containing the part to be ex-
amined as before indicated. The centering
point 11 of the interrupter unit is then pressed
against the center of the end of a convenient
shaft rotating at a suitable speed relative to
the frequency of the cyclic operation of the
part to be examined (usually a shaft of the
machine being examined), so that the inter-
rupter shaft 6 is driven, say, at the same speed
as the shaft to which it is applied. What con-
stitutes a suitable speed for the machine shaft
driving the interrupter shaft will be under-
stood by those skilled in this art, but for the
purposes of this explanation will be assumed
to be such a speed that the machine shaft
makes one revolution while the part to be ex-
amined moves through one complete cycle. The
interrupter may be held against the machine
shaft by hand, or clamped in place, the sleeve
affording a convenient part for clamping pur-
poses as will be apparent. In the alternative,
a separate motor may be used to drive the in-
terrupter. With the interrupter shaft in its
innermost or righthand position as shown in
Fig. 3, the primary circuit of the transformer
is interrupted once during each rotation of the
interrupter shaft, each interruption causing the
induction of a train or group of voltage waves
in the secondary circuit which gradually de-
crease in value during the period in which the
primary circuit is open. A train of such waves
is conventionally shown by the curve 37 in
Fig. 6. The apparatus is intended to be so de-
signed that only one wave or half cycle of
75

each train is of sufficient amplitude to produce illuminating current in the illuminator A. The line 36 being the zero line, the broken lines 36^a may be regarded as indicating the value of voltage sufficient to light the illuminator. By this means therefore, the illuminator A produces a single and almost instantaneous flash of light each time the contacts 16 and 18 are operated and the rotations of the shaft 6 being synchronous with the cyclic movements of the part to be examined, all these flashes occur at the same point in the cycle of the part being examined. When the illuminator A therefore is approached to and directed toward the moving part to be examined, this part is illuminated when, and only when, it is at some certain point or stage of its cycle and hence appears to the eye to be standing stationary at this point. To view the moving part in some point of its cycle other than that in which it is first seen, the angular relation of the lever 15 to the shaft cam must be changed, which can be done with the greatest convenience by simply turning the cover 4 and thereby the head 1. This makes the light flashes occur earlier or later in the cycle. The amount of this angular shift, or the difference in phase between any two certain positions of the moving part under examination, can be measured by thus turning the cover 4 with respect to the sleeve 3 and noting thereby the angular distance through which the lever 15 must be carried to change the view from one of these positions to the other. For this purpose, I usually provide a pointer 26 secured by a post 27 to the sleeve 3 in juxtaposition to a scale 28 marked circumferentially, usually in degrees, on the cylindrical surface of the cover 4 adjacent thereto. By pulling out the shaft 6 to its left hand position (or, contra, pulling the cover 4 and head to the right away from the sleeve 3), so as to bring cam 13 into action, the moving part can be viewed in two positions simultaneously, namely (because cams 12 and 13 are separated by 180°) at opposite points in its cycle. The moving part may be made to appear as though moving slowly, "creeping", in its proper direction, by slightly releasing the pressure of the center point on the driving shaft so that a small degree of slip occurs and the interrupter shaft 6 rotates slightly slower than the driving shaft. By driving the interrupter at a greater speed the moving part can be made to appear moving slowly backwards.

A flash-illuminating stroboscope of the general type described (omitting reference to the present invention) is subject to the limitation that it produces sharp and well defined images only within a limited range of speed; that is to say, if the instrument is designed for successful operation at low shaft speeds, then it fails entirely at materially higher shaft speeds; or if designed for high speeds, then it produces poorly outlined images at materially lower speeds, or even two or more images slightly displaced from each other where only one should be seen. This, I believe I have discovered, is due to the time-constant of the transformer and the varying periods of energization. That is to say, the inductance in the primary circuit delays the building up of the current in this circuit, so that it grows or only builds up slowly following each closing of the primary circuit at the contacts 16 and 18, and its ultimate value depends on the length of time the contacts are held closed.

At slow speeds the contacts are permitted to remain closed for longer periods than at high speed, and accordingly the primary currents reach higher values at low speeds than at high and hence energize the magnetic field more highly, i. e., produce a greater number of magnetic flux lines in it. Accordingly the voltages induced in the secondary winding vary inversely to the speed. Assuming, for example, that the transformer is so constructed that the short closing-periods of the contacts at high speeds are long enough to build up the magnetic field to a value capable of inducing a voltage wave-train in the secondary winding having one wave of sufficient amplitude to light the illuminator A (i. e. greater than the voltage indicated by the broken line 36^a in Fig. 6 previously referred to), then at low speed, when the contacts 16 and 18 are allowed to remain closed for longer periods of time, the magnetic circuit is so much more highly energized that it induces wave trains, each of which has two or more waves or half cycles of sufficient amplitude to produce flashes in the illuminator, so that the resulting images are indistinctly outlined or multiple images are produced where only one should be seen. Contra, if the transformer is so constructed, that at low speeds the magnetic field builds up to a value only sufficient to induce one wave of sufficient amplitude to light the illuminator, then at high speeds (the windings being neither increased nor diminished and all other things remaining unchanged) the magnetic circuit is so incompletely energized during each short charging period that the resulting wave trains have no waves of sufficient amplitude to light the illuminator, and the apparatus fails entirely. To operate throughout a wide speed range therefore it is only necessary to compensate for the variations in the length of the periods in which the contacts are held closed (or the variations in the ratio of contact-open periods to the contact-closed periods) to the end of maintaining the product of the number of effective or active turns in the secondary winding, multiplied by the number of magnetic flux lines cutting the said secondary per unit of time, within such limits that each induced voltage-train has one wave, and only one wave, of sufficient amplitude to light the illuminator.

It will be apparent upon consideration that increasing the number of interruptions of the primary circuit per rotation of the interruptor shaft (to display the part under examination in two or more positions simultaneously) acts in exactly the same manner as increasing the speed of the operating shaft, so that a stroboscope without my invention may function quite satisfactorily at a certain speed when producing one view per cycle, but fail when used to produce two or more views per cycle at the same speed. Obviously the reverse is also true. My invention may be used to correct for this also, as is quite apparent.

Preferably I compensate for changes in the periods of the contact operation which accompany changes in the frequency of operation, by counteracting the tendency for the maximum or ultimate strengths of the magnetic field to vary, specifically by changing the time-constant of the primary or inducing circuit inversely to the change of speed; more preferably by changing the inductance of the primary circuit, and more preferably still by reducing the inductance of the primary circuit by cut-

ting out transformer-primary turns when the speed is increased, and increasing the same inductance by cutting in turns when the speed is reduced, thus speeding up the creation of the magnetic field with increasing speed and delaying the building up of the field as the speed is reduced, so that at every speed the magnetic circuit is energized sufficiently to light the illuminator but at no speed is the field energized sufficiently to produce two voltage waves in a single train of sufficient amplitude to light the illuminator. It is not necessary that the strength of the field bear a close relation to the speed, and this is especially true where the discharge is highly damped, so that there is a wide difference in amplitude between the maximum wave and the next highest in the train. High damping in itself, it will be observed, broadens the range of speed (i. e., contact frequency) that can be covered without any change in the circuits or apparatus, inasmuch as it permits considerable difference between the lowest speed which produces a train of waves 37 (Fig. 6) whose second highest wave 38, for example, is less than 36° and hence is insufficient to light the illuminator, and the highest speed which produces a wave train 39 whose maximum wave is sufficient to light the illuminator. I have found three or four adjustments of the number of primary turns are sufficient to cover the entire range of speed usually encountered in practice. The taps 40 and 41 in the primary circuit of the transformer, in conjunction with the terminal connection 42 provide for three changes in the inducing circuit inductance. The tap switch B1 with its movable switch arm is a convenient means for changing the connections to any one of these leads. For the highest speeds the magnetizing current is made to travel the tap 40 and hence only the smallest part of the primary circuit. Accordingly the magnetic field is built up rapidly. For the lowest speeds the terminal connection 42 and the entire primary winding are utilized, and hence the magnetic field is built up much more slowly. At some certain intermediate speeds the tap 41 and an intermediate part of the primary winding are resorted to so that the magnetic field builds up at an intermediate rate. While the proper location of the higher speed taps in a winding satisfactory as a whole for low speed work, can be predetermined to some approximate degree as appears from the foregoing, the subject of induction coils and oscillating transformers of the type used in this work is so far from having been reduced to exact calculation, it will be understood, that the best location of the taps may require experiment and trial on each size and type of apparatus. It must also be understood that regardless of the correctness of my theories of the cause of the fault and its counteraction as above explained, the fact is that taps such as 40, 41, etc., suitable locations for which can be found readily, when utilized in the manner described, do act to adapt the instrument to produce sharp and well defined images throughout substantially the wide range of speeds usually encountered in practice.

The inductance and hence the time-constant of the primary circuit can also be varied in other ways as will be understood by those skilled in the art.

In the foregoing I have assumed that the voltage at the source 20 remains substantially constant. The time required to build up the

magnetic field to any predetermined value varies of course, inversely with the value of the voltage applied to the primary winding of the inductor at B. As an alternative therefore, the tendency for the field strength to vary with the frequency of contact operation can be compensated for and counteracted by suitably varying the voltage of the source 20, using higher source voltages with the higher speeds and lower source voltages with lower speeds. The same result can be obtained without varying the source voltage, by adding ohmic resistance in series with the primary winding as the speed is increased and reducing the resistance of the primary circuit as the speed is reduced. The latter is illustrated in Fig. 7 wherein the box B with its transformer or induction coil, leads A2 and 34 and current source 20 of Fig. 1, will be recognized; in lieu of the switch B' and primary winding taps of Fig. 1, a manually-variable resistance B'' is provided in series with the primary winding, the amount of the resistance element 50 in the primary circuit being variable at will by turning the pivoted lever 51.

Furthermore the capacity of the condenser 19 affects the range of operations. By suitably reducing the capacity at this point as the speed is increased and increasing the capacity for reduced speeds, the range of operation of the instrument can be increased. This is not so desirable as the use of the tapped primary however, because the tapped primary operation entails a higher resistance in the primary circuit with the lower speeds and thus is more economical in battery consumption.

While I have thus described what I believe to be the best forms of my invention, it will be understood that my invention is not limited thereto except as hereinafter appears in the claims. Furthermore, it will be understood that my present invention is not limited to the particular stroboscopic apparatus illustrated and described; for the most part this particular stroboscopic apparatus is intended to be merely representative of the type of apparatus to which the present invention is applicable.

I claim:

1. In stroboscopic apparatus, the combination of a flash-illuminator, an induction apparatus for supplying lighting currents thereto, contacts to open and close the primary circuit of said induction apparatus to produce lighting currents, and means to change the time constant of said primary circuit.

2. In stroboscopic apparatus, the combination of a flash-illuminator, an induction apparatus for supplying lighting currents thereto, contacts to open and close the primary circuit of said induction apparatus to produce lighting currents, and adjustable means connected to said primary circuit to change the time constant of said primary circuit.

3. In stroboscopic apparatus, the combination of a flash-illuminator, an induction apparatus for supplying lighting currents thereto, contacts to open and close the primary circuit of said induction apparatus to produce lighting currents, and adjustable means to change the value of the currents produced in said primary circuit during the periods when said contacts are closed.

4. In stroboscopic apparatus, the combination of a flash-illuminator, an induction apparatus for supplying lighting currents thereto, contacts to open and close the primary circuit of said in-

duction apparatus to produce lighting currents, and an adjustable resistance connected to said primary circuit to carry primary-circuit current.

5. In stroboscopic apparatus, the combination of a flash-illuminator, an induction apparatus for supplying lighting currents thereto, contacts to open and close the primary circuit of said induction apparatus to produce lighting currents, means providing current for said primary circuit, and an adjustable resistance connected in series with said primary circuit and said means.

6. In stroboscopic apparatus, the combination of a flash-illuminator, an induction apparatus for supplying lighting currents thereto, contacts to open and close the primary circuit of said induction apparatus to produce lighting currents, means for providing current for said primary circuit, and adjustable means for varying the 20 voltage applied to the primary circuit by said current-providing means.

7. In stroboscopic apparatus, the combination of a flash-illuminator, an induction apparatus for supplying lighting currents thereto, contacts to open and close the primary circuit of said induction apparatus to produce lighting currents, condenser means connected to said primary circuit, and adjustable means for changing the effective capacity of said condenser means.

8. In stroboscopic apparatus, the combination with a flash-illuminator, an induction apparatus for supplying lighting currents thereto, and contacts to close and open the primary circuit of said induction apparatus to produce lighting currents, of means for enlarging the range of frequencies of contact operations throughout which sharp and well defined images are produced, comprising means for compensating for the tendency of the product of the number of 35 turns in the secondary winding of said induction apparatus, multiplied by the rate of change of the inducing magnetic flux, to change with the frequency of operation of the contacts.

9. In stroboscopic apparatus, the combination with a flash-illuminator, an induction apparatus to provide lighting currents therefor, and controlling contacts in the primary circuit of said induction apparatus, of means for changing the inductance of said primary circuit.

10. In stroboscopic apparatus, the combination of a flash-illuminator, an induction apparatus having primary and secondary circuits to provide lighting currents therefor, and contacts to open and close the primary circuit of said induction apparatus, characterized by the fact that separate taps are provided in the primary winding of said induction apparatus.

11. The method of obtaining sharp and well defined images, from a flash-illuminating stroboscopic apparatus, at different frequencies of flashes, which consists in maintaining the product of the number of active secondary turns of the induction apparatus, multiplied by the number of magnetic flux lines cutting the said secondary turns per unit of time, within such limits that each induced voltage-train has one wave, and substantially only one wave, of sufficient amplitude to light the illuminator.

12. The method of increasing the flash-fre-

quency range of operation of flash-illuminating stroboscopic apparatus, which consists in maintaining, throughout the range of operations, the product of the number of active secondary turns of its induction apparatus, multiplied by the number of magnetic flux lines cutting the said secondary turns per unit of time, within such limits that each induced voltage train has one wave, and substantially only one wave, of sufficient amplitude to light the illuminator.

13. The method of obtaining sharp and well defined images, from a flash-illuminating stroboscopic apparatus, throughout a range of flash frequencies, which consists in counteracting the tendency of the product of the number of active 15 secondary turns in the inducing apparatus, multiplied by the rate of change of the magnetic flux thereof, to change with the frequency of the flashes.

14. The method of obtaining sharp and well 20 defined images, from a flash-illuminating stroboscopic apparatus, throughout a range of flash frequencies, which consists in restraining the inherent tendency of the strength of the inducing magnetic field to vary with the frequency of 25 the flashes.

15. The method of increasing the flash-frequency range throughout which a flash-illuminating stroboscopic apparatus produces sharp and well-defined images which consists in counteracting the inherent tendency of the strength of the inducing magnetic field to vary with the frequency of the flashes, thereby maintaining the strength of the magnetic field, throughout the range, within limits suited to produce a 30 single voltage wave, and substantially only a single voltage wave, at each operation of the contacts, of sufficient amplitude to light the illuminator.

16. The method of enlarging the range of 40 flash-frequencies throughout which a flash-illuminating stroboscopic apparatus produces sharp and well defined images, which consists in changing the time-constant of a circuit of the inducing apparatus in a direction to compensate for changes in the periods of the operation of the controlling contacts which accompany changes in the frequencies of the flashes.

17. The method of operating flash-illuminating stroboscopic apparatus to increase the flash-frequency range of operations, which consists in changing the value of the time-constant of the inducing circuit of the induction apparatus, in a direction inverse to the change in the frequency of the flashes.

18. The method of operating flash-illuminating stroboscopic apparatus which consists in changing the inductance of the primary circuit of the induction apparatus in a direction inverse to the change in the frequency of the flashes.

19. The method of increasing the range of flash-frequencies of a flash-illuminating stroboscopic apparatus, which consists in reducing the number of active primary inducing turns in the induction apparatus when the frequency of the flashes is increased, and increasing the number of active turns of said winding when the frequency of the flashes is reduced.

PETER DAVEY.
